UNITED STATES PATENT OFFICE.

EDWARD O. WARNER, OF PHILADELPHIA, PENNSYLVANIA, ASSIGNOR TO LATROBE STEEL & COUPLER COMPANY, OF PHILADELPHIA, PENNSYLVANIA, A CORPORATION OF NEW JERSEY.

COUPLING.

SPECIFICATION forming part of Letters Patent No. 734,782, dated July 28, 1903.

Application filed April 7, 1903. Serial No. 151,434. (No model.)

To all whom it may concern:

Be it known that I, EDWARD O. WARNER, a citizen of the United States of America, residing in the city and county of Philadelphia, in the State of Pennsylvania, have invented a certain new and useful Improvement in Couplers, of which the following is a true and exact description, reference being had to the accompanying drawings, which form a part thereof.

My invention relates to railroad-couplers, and has for its object particularly the improvement in the locking-pin and its immediate connections and coacting parts, with a particular view, in the first place, of facilitating the movement of the locking-pin from a "set" position to one in which it is enabled to fall to locking position, and, in the second place, to provide an improved construction and combination of locking and lifting pin sections which is well adapted to prevent the creeping of the pin and is also well adapted to provide for the lifting of the pin in case of the breaking loose of the draw-head.

The nature of my improvements will be best understood as described in connection with the drawings in which they are illustrated, and in which—

Figure 1 is a plan view of my improved coupling-head with the jaw connected therewith, but with the locking and lifting pin sections removed. Fig. 2 is a side view of the coupling-head and draw-bar, shown partly in section on the line 2-2 of Fig. 1 and with the pin illustrated in locking position. Fig. 3 is a similar side view with the locking-pin shown in set position and the lifting-pin section turned backward, showing its capacity for such turning motion. Fig. 4 is a rear view of the two sections making up the pin, the said parts being shown disassociated; and Fig. 5 is a front view of the pin-sections, shown also in disassociated positions.

A indicates the coupling-head formed, as is usual, integral with the draw-bar portion A'.

A² indicates the top, and A³ the bottom or floor, of the chamber formed in the head and wherein the tail of the knuckle moves.

A⁴ indicates the locking-pin hole, which where it passes through the floor of the cham-

ber formed in the head is, in accordance with my present invention, formed with a lateral wall a⁴, inclined forwardly and inwardly, as shown, instead of forming a continuation of the lateral wall bounding the upper portion 55 of the pin-hole. By preference I also form the wall a⁵ with an inward and forward inclination, as shown, and form in the floor of the chamber, immediately in front of this wall, an inclined notch, as indicated at a⁸. 60

B indicates the knuckle pivoted to the head, as is shown, and having a tail, (indicated at B').

C is a removable abutment or shoulder, shown here as a bolt-section, which extends 65 through the upper portion of the pin-hole A⁴, as shown, and can be removed to permit the insertion or withdrawal of the locking-pin section.

D is the locking-pin section, formed with a 70 prolongation which extends through the pin-hole formed in the floor of the chamber and which prolongation has, as shown, an extension D', which always remains within the pin-hole formed in the bottom and immediately 75 in front of which lies the inclined shoulder, (indicated at d'). The upper portion of the locking-pin D is by preference formed with a rearwardly and downwardly inclined top (indicated at D²) and with a rearwardly and 80 downwardly inclined groove (indicated at D³) and which communicates with the top of the pin through a slot D⁴, the walls d⁴ on each side of this slot lying over the lateral portions of the grooves or recesses D³. The pin is also 85 formed with a shoulder D⁶, extending rearward of the grooved and slotted portions, as shown. The groove D³ extends upward from the rear face of the upper portion of the pin and terminates in a shoulder, (indicated 90 at D⁵.)

E indicates the lifting-section of the pin and has by preference its lower end E² formed on an inclination which corresponds to the inclination D² of the upper end of the locking-pin, and from the lower end of the pin E extends the tongue E³, which is adapted to pass freely through the slot D⁴ and has extending laterally from it trunnions E⁴ E⁴, which are enabled to pass freely into the groove or open- 100

ing D³ until they come in contact with its top shoulder D⁵.

E⁵ indicates the top of the pin E, by which it is attached to an ordinary lifting-chain 5 (not shown) and which is preferably formed with a shoulder e⁵, which, when the pin is in locking position, should rest upon the top wall surrounding the pin-hole in the head. The lifting-pin section is also provided with a rearwardly-extending shoulder E'.

In operation the pin when in locking position occupies the position shown in Fig. 2, the lifting-section E being somewhat thrust backward, so that its shoulder E' extends below the pin or shoulder C, and it will be obvious that if for any reason force is exerted on the locking-pin section D, tending to lift it, it will press the lifting-pin E backward and force the shoulder E' still more firmly 20 beneath the abutment C, in this way effectually locking the lifting-pin section and through it the locking-pin section against all forces tending to raise them except those exerted through the lifting-pin section. When 25 it is desired to unlock the knuckle, the locking-pin is drawn up by the lifting-pin section, which in the act of drawing up is thrown forward to clear the shoulder C, and when the pin D has been raised to a position where it 30 clears the tongue B' of the knuckle it is canted or tilted forward, so that its inclined shoulder d' is thrown over the front wall a⁵ of the pin-hole formed in the floor of the chamber, engaging the sloping notch a³, as is 35 shown, for instance, in Fig. 3. The knuckle-tail is then enabled to pass forward to the position shown in dotted lines in Fig. 1, its shape being such that as it is moved forward it gradually pushes backward on the tail of 40 the locking-pin until it pushes the shoulder d' over the edge of the wall a⁵, whereupon the pin is free to drop until its enlarged portion rests upon the tail of the knuckle and when 45 the knuckle is returned to its engaging position (shown in full lines in Fig. 1) is free to trip to locking position, as shown in Fig. 2. It is to facilitate the backward motion of the locking-pin that I give to the wall a⁴ the inclination shown in Fig. 1, this construction 50 greatly diminishing friction and enabling the pin to be moved with much less effort than has heretofore been the case. In normal operation the lifting-pin section E moves practically up and down with a slight shifting 55 forward and back; but in case the draw-bar breaks loose from the car and the coupling-head is drawn forward the lifting-pin section E is free to turn backward on its trunnions E⁴, as shown in Fig. 3, and this results in the 60 drawing up of the locking-pin section, so that before the draw-bar and coupling-head is entirely disconnected from the hangers on the car the knuckle will open and permit the connected car to move freely away, thereby 65 releasing the strain tending to draw the head and draw-bar entirely loose from the car and drop it upon the track.

Having now described my invention, what I claim as new, and desire to secure by Letters Patent, is—

1. The coupler-head having a pin-hole formed in it for the locking-pin, said pin-hole having, where it passes through the floor of the chamber in the head, a forwardly and inwardly inclined wall a⁴. 75

2. The coupler-head having a pin-hole formed in it for the locking-pin, said pin-hole having, where it passes through the floor of the chamber in the head, forwardly and inwardly inclined walls a⁴, a⁵. 80

3. The coupler-head having a pin-hole formed in it for the locking-pin, said pin-hole having, where it passes through the floor of the chamber in the head, forwardly and inwardly inclined walls a⁴, a⁵, and an inclined 85 recess a³, at the edge of wall a⁵.

4. In combination with a coupler-head having a locking-pin hole, the coupler locking-pin having a rearwardly and downwardly inclined recess D³, and a groove D⁴, leading 90 through the top of the pin into said recess and the lifting-pin having a downwardly-extending tongue adapted to pass through groove D⁴, and laterally-extending trunnions E⁴, E⁴, adapted to enter the recess D³, and 95 engage the walls of the groove, whereby the lifting-pin is enabled to turn backward as on a hinge, without disengaging the locking-pin.

5. In combination with a coupler-head having a locking-pin hole, the coupler locking-pin having a rearwardly and downwardly inclined upper end, formed with an inclined recess D³, and a groove D⁴, leading through the inclined top of the pin into said recess, and the lifting-pin, having a downwardly-extending tongue adapted to pass through groove D⁴, and laterally-extending trunnions E⁴, E⁴, adapted to enter the recess D³, and 100 engage the walls of the groove, whereby the lifting-pin is enabled to turn backward as on a hinge, without disengaging the locking-pin. 105

6. In combination with a coupler-head having a locking-pin hole, the coupler locking-pin, having a rearwardly and downwardly inclined upper end, formed with an inclined 110 recess D³, and a groove D⁴, leading through the inclined top of the pin into said recess, and the lifting-pin having its lower end inclined to conform to the inclination of the locking-pin, a downwardly-extending tongue 115 adapted to pass through groove D⁴, and laterally-extending trunnions E⁴, E⁴, adapted to enter the recess D³, and engage the walls of the groove, whereby the lifting-pin is enabled to turn backward as on a hinge, without disengaging the locking-pin, said lifting-pin 120 having also a rearwardly-extending shoulder adapted, when the connected pins are in their lowermost positions, to engage under a ledge in the pin-hole of the coupler. 125

7. In combination with a coupler-head having a locking-pin hole and a removable shoulder or ledge C, extending across the rear side of said hole, the coupler locking-pin, having 130

a rearwardly and downwardly inclined upper end formed with an inclined recess D^3 , and a groove D^4 , leading through the inclined top of the pin into said recess, and the lifting-
5 pin, having its lower end inclined to conform to the inclination of the locking-pin, a downwardly-extending tongue adapted to pass through groove D^4 , and laterally-extending trunnions E^4 , E^4 , adapted to enter the recess
10 D^3 , and engage the walls of the groove, whereby the lifting-pin is enabled to turn back-

ward as on a hinge, without disengaging the locking-pin, said lifting-pin having also a rearwardly-extending shoulder adapted, when the connected pins are in their lowermost positions, to engage under the ledge C , in the pin-hole of the coupler. 15
